CHAIN TIGHTENER

Charlie M. Livingston, Tulsa, Okla., assignor to
 The J. E. Shaffer Company, Tulsa, Okla., a
 co-partnership composed of J. E. Shaffer and
 J. L. Smith

Application January 18, 1935, Serial No. 2,429

3 Claims. (Cl. 254—74)

The invention relates to chain tighteners particularly adapted for use in connection with load holders or binders, and has for its object to provide a chain tightener having a body through which one portion of a load tightening chain may be passed without feeding the end through the body, thereby allowing the application of the body to the chain at a point spaced from its end.

A further object is to provide a chain tightener with a chain receiving chamber extending entirely through the same in communication with a narrower chamber extending the full length of the body and entirely through one side of the body, thereby allowing the operator to easily feed the end of the chain through the body or a portion of a bight of a chain if desired.

A further object is to provide one end of the body with a shackle arching the end of the body and the end of the chamber extending through the body, thereby allowing the feeding of a portion of a bight of chain through the body. Also to provide the shackle with means for receiving and holding a chain end.

A further object is to provide an oscillating lever pivotally connected to the body member and having pawl means extending into the chamber of the body and cooperating with the chain therein for imparting a pull on the chain end within the body; said pawl means forming locking means for holding the chain against retrograde movement.

A further object is to provide the oscillating handle with pawls pivoted at opposite sides of the pivotal point of the handle and cooperating with links of the chain whereby a double acting pull is imparted on a chain end. The double acting pawls also form holding means for positively holding the chain end against retrograde movement when the operating handle is at the ends of its movement or in an intermediate position.

A further object is to form the chamber in the body T-shaped in cross section so that the alternate links of the chain will be guided in planes at right angles to each other. Also to provide the ends of the pawls with recesses adapted to receive the upper sides of the vertical links during the tightening operation.

With the above and other objects in view the invention resides in the combination and arrangement of parts as hereinafter set forth, shown in the drawing, described and claimed, it being understood that changes in the precise embodiment of the invention may be made within

the scope of what is claimed without departing from the spirit of the invention.

In the drawing:

Figure 1 is a perspective view of the chain tightener showing the handle member in an intermediate position.

Figure 2 is a vertical longitudinal sectional view through the chain tightener showing the same with its handle in forward locked position.

Figure 3 is a perspective view of the chain tightener showing the method of feeding a portion of a bight of chain through the body.

Figure 4 is a perspective view of one of the lever dogs.

Referring to the drawing, the numeral 1 designates the body of the tightener, and which body is provided with an elongated chamber 2 having at its opposite sides apertured ears 3, to which are pivotally connected the arms 4 of the bifurcated handle member 5, which is adapted to be oscillated for imparting an intermittent pull on the chain end 6 in the direction of the arrow a. The other end of the chambered body member 1 is provided with a boss 7 to the opposite sides of which are pivoted the arms 8 of a chain end 25 receiving shackle 9. The notch 10 is adapted to receive the chain end 11 and the device as a whole is adapted to tighten a chain around a load on a vehicle or where ever it is desired to tighten a chain; applicant does not limit himself in this particular.

Pivots connected between the arms 4 of the handle member 5 is a forwardly extending dog 12, the free end of which terminates in downwardly extending spaced jaws 13 having a groove 35 14 therebetween and through which groove the vertical links 15 of the chain end 6 slide during the oscillation of the handle member 5.

The dog 12 is pivotally connected at 16 to the handle member 5 to the outside of the pivotal point of the handle member, therefore it will be seen that when the handle member is moved in the direction of the arrow b, Figure 2, the jaws 13 of the dog will engage the inner end of one of the horizontal links 17 as clearly shown in Figure 2, and will impart a pull on the chain end 6 in the direction of the arrow a. Pivotally connected to the arms 4 of the handle member 5 and below the pivotal point of the handle 5 at 18 is a second dog 19 having jaws 20 which cooperate with the inner ends of the horizontal links 17, and it will be seen that upon oscillation of the handle member 5, a pull will be imparted on the chain end 6 alternately upon each oscillation of the handle, thereby providing an intermittent but 55

substantially continuous pull on the chain end. It will be noted that by positioning the pivotal points of the dogs 12 and 19 on opposite sides of the pivotal point of the handle 5 and all of 5 said parts on the same side of the chain end, when the handle is in its forward position as shown in Figure 2, the strain in a reverse direction on the chain 6 will cause the dogs to positively hold the chain end 6 against retrograde 10 movement; therefore there is a locking device at the forward end of the stroke of the handle. The locking of the handle when in forward position as shown in Figure 2 is caused by the pawls 12 and 19 engaging the inner ends of spaced links 15 with their noses 13 and 20 in engagement with the links and the pivoting of the pawls at 16 and 18 on opposite sides of the pivotal point of the handle. Therefore it will be seen that retrograde strain on the chain end will apply strain to the 20 handle member 12 on opposite sides of its pivotal point, and this strain will be equalized through the pawls 12 and 19 therefore it will be seen that there is a positive holding of the handle against rearward movement. As the handle is oscillated rearwardly, reference being had to Figure 2, it will be noted that the dog 19 will force the chain end in the direction of the arrow *a* and the dog 12 will ride over the next horizontal link 17, reference being had to Figure 2, until it engages 30 the rear side of the next horizontal link, and when in this intermediate position the chain will be also positively held by the cooperation of both dogs therewith. The holding of the handle 5 in the intermediate position as shown in Figure 1 35 is accomplished when the dog noses 13 and 20 are in engagement with the inner ends of adjacent horizontal links 17 and at which time the strain is still applied to the handle member 5 on opposite sides of its pivotal point through the 40 medium of the dogs 12 and 19, all of said parts being located on the same side of the chain. In all of the positions, either forward, intermediate or rear, there is an equalization of strain on the handle at opposite sides of its pivotal point, 45 through the dogs and which strain is equalized in relation to the pivotal point hence there is a positive holding of the handle against rearward movement, but freedom for manual movement forwardly at all times.

50 A further locking position takes place when the handle member 5 is in extreme rear position, and when in such position the dog 19 is in extreme forward position with its pivotal point in a position where it has passed through a line between 55 the jaws 20 thereof and the pivotal point of the handle 5. When in this position the chain end 6 is positively held against retrograde movement by the single dog 19, and now the dog 12 is raised out of cooperative relation to the chain by the 60 dog 19 in its forward movement. By providing these various locking positions, it is obvious that a very fine adjustment or tightening may take place, even as low as taking up the slack of a single link.

65 One of the main difficulties experienced with chain tighteners as at present constructed is that no means is provided whereby a bight of chain may be passed therethrough without the necessity of passing the end of the chain through the device and reeving the entire chain no matter how long, through the device until it assumes the proper position. This is a laborious operation, particularly where the chain is heavy and an impossible one where the chain end is otherwise an-

chored. To obviate the above difficulty the under side of the body 1 is provided with an elongated slot 21 in communication with the chamber 2 and extending the full length of the device, as clearly shown in Figure 3, which shows the operation of 5 placing a portion of a bight 22 in the device. When doing this the bight is held as shown in Figure 3, and the body 1 preferably in the vertical position shown, is then passed downwardly over the vertical portion 23 of the chain bight 10 until the upper end of said portion 23 is passed through the end of the body having the shackle 8 attached thereto.

By providing the shackle 8 arching the end of the body member 1 it will be noted that the chain 15 end may easily feed from the end of the body member on the line of pull. The slot 21 is narrower than the width of the links, hence only the lower portions of the vertical links 15 extend therethrough; the horizontal links being guided 20 by the walls of the chamber 2.

From the above it will be seen that a chain tightening device is provided which is particularly adapted for use as a load holder or boomer, and that there is a double action during the oscillation of the handle member 5, and that said handle member will be held by retrograde strain on the chain end in several positions thereby allowing the taking up of a relatively short amount of slack and obviating the necessity of providing 30 separate chain holding means after the chain tightening operation. It will also be seen that a portion of a bight of chain may be passed through the device thereby obviating the necessity of passing the end of the chain through the device, and at the same time allowing the chain tightener to be applied to a chain over a load with its ends anchored and in a manner whereby slack in the 35 chain may be taken up.

The invention having been set forth what is 40 claimed as new and useful is:

1. A chain tightener comprising a body member having a chain receiving chamber extending entirely therethrough and through one side of the body member throughout its length thereby 45 allowing a portion of a bight of chain to be passed entirely through the body member and means carried by the body member and cooperating with the chain within the chamber for imparting a pull thereon.

2. A chain tightener comprising a body member having a chain receiving chamber extending entirely therethrough and through one side of the body member throughout its length and forming means whereby a chain bight may be passed 55 through the body member, means for imparting a pull on a chain within the chamber of the body member, a shackle carried by one end of the body member and arching the end of the chamber and chain end attaching means carried by said 60 shackle.

3. A chain tightener comprising a body member having a chain receiving chamber extending entirely therethrough and through one side of the body member throughout its length, an oscillating lever carried by the body member and pivotally connected thereto, a pair of dogs pivoted to the lever at opposite sides of the pivotal point of the lever, said dogs, upon oscillation of the lever, intermittently imparting a pull on a chain 70 in the chamber, said dogs forming locking means for the chain when the lever is in forward, intermediate or rear positions.

CHARLIE M. LIVINGSTON.
